[57] CLAIM

The ornamental design for a bottle cap, as shown and described.

DESCRIPTION

FIG. 1 is a perspective view of a bottle cap showing our new design.

FIG. 2 is an enlarged side elevational view thereof;

FIG. 3 is an end elevational view thereof;

FIG. 4 is a top plan view thereof; and

FIG. 5 is a bottom plan view thereof.

The broken lines representing the receptacle in FIG. 1 on the drawing are shown for illustrative purposes only.
